UNITED STATES PATENT OFFICE.

PATRICK GRANGER, OF LAS CRUCES, NEW MEXICO.

VIBRATOR STRUCTURE.

Application filed April 13, 1927. Serial No. 193,503.

The present invention relates to combined hair clippers and vibrator and has for its principal object to provide a very compact and convenient structure which contains an 5 electric motor for the operation of hair clippers through gearing, which may be disconnected to provide a loose element which will set up vibration.

A still further very important object of the 10 invention lies in the provision of a combined structure of this nature, which is exceedingly simple in its formation of parts and arrangement, which may be manufactured at a low cost and yet prove thoroughly efficient and 15 reliable in operation and strong and durable in construction.

A still further very important object of the invention resides in the provision of a structure of this nature, which is not likely to 20 easily become out of order, may be readily handled without much effort and is otherwise well adapted to the purpose for which it is designed.

With the above and numerous other objects 25 in view as will appear as the description proceeds, the invention resides in certain novel features of construction and in the combination and arrangement of parts as will be hereinafter more fully described and claimed.

30 In the drawing:

Figure 1 is a sectional side elevation of a device of this nature, embodying the features of my invention.

Figure 2 is a top plan view thereof showing 35 portions in section.

Figure 3 is a transverse section taken substantially on the line 3—3 of Figure 1.

Figure 4 is a detail plan view of the clippers.

40 Figure 5 is a detail plan view of one of the gears.

Figure 6 is a detail perspective view of a yoke on said gear, and

Figure 7 is a detail perspective view of the 45 drive shaft.

Referring to the drawing in detail, it will be seen that the numeral 5 denotes the casing which has mounted therein an electric motor 6, the shaft of which continues into a 50 drive shaft 7, which is journaled through an opening 8 at one end of the casing and merges into a flat enlargement 9, the intermediate portion 10 of which is narrowed gradually toward the body of the shaft 7, as will be apparent from an inspection of Figure 1. A plate 11 is riveted or otherwise secured as at

12 to the casing 5 and extends forwardly therefrom and is inclined upwardly at its extremity as at 14. A clipper guard 15 is fixed to the portion 14, and slidably supports 60 a cutter member 16, which has a recess 17 at one edge thereof for receiving one end of a lever 18, which is rockably supported on a pin 19. The other end slides in a yoke 20, which has a stem 21 rotatable in an off-center 65 opening in a bevelled gear 23. This bevelled gear 23 is journaled for rotation above the plate 11. A frame F comprises a pair of spaced parallel plates 24, with openings 25, these plates being connected by a curved intermediate portion 26. A gear 27 of the bevelled type has a slot for receiving the flat end 9 of the shaft 7 to slide thereon and is disposed between the plates 24 to be shifted by the frame F in and out of mesh with the gear 70 23. A plate 29 extends from the top of the casing 5 forwardly and is slotted, as at 30, to receive a bolt 31, from the intermediate portion 26 and a nut 32 is on the bolt, so that the frame F may be held in different positions. The plate 29 merges into an inclined 75 portion 34, which has a pressure bar 35 at the extremity thereof actuated by a key pressure screw 36.

A pair of spring loops 38 and 39 are 80 mounted in spaced relation on the plate 11.

When the structure is to be used for clipping hair, the parts are disposed as is shown in Figure 2, and the use thereof will be quite apparent. Now to use the structure as a vibrator, the frame F is shifted rearwardly until the gear is disposed over the narrow portion 10 of the flat shaft portion 9, whereby it will be seen that the gear 27 will wobble considerably when the shaft 7 is in rotation, thus 90 causing a vibration of the whole structure. The operator may put his hand through the spring loop 39 and two fingers through the loop 38 and then by rubbing the other fingers of the hand on the head or face of the 95 customer, the desired vibration will be set up.

It is thought that the construction, operation and advantages of this invention will now be quite apparent without a more detailed description thereof. It will be seen 100 that the device is exceedingly simple and will be exceedingly useful around an ordinary barber shop. The structure may be made light and because it contains the motor is capable of being used over a larger range 105 by a suitable length extension cord as will be quite apparent. The device can be easily 110

manipulated to be transferred from a hair clipper to a vibrator, and vice versa.

The present embodiment of the invention has been disclosed in detail merely by way of example, since in actual practice it attains the features of advantage enumerated as desirable in the statement of the invention and the above description. It will be apparent that changes in the details of construction and in 10 the combination and arrangement of parts may be resorted to, without departing from the spirit or scope of the invention as hereinafter claimed or sacrificing any of its advantages.

Having thus described my invention, what 15 I claim as new is:

A vibrator structure of the class described comprising a motor, a shaft operatively associated with the motor and merging into a flattened portion, the intermediate part of 20 which is narrowed, an element having a slot for receiving the flattened portion so that the said element may be disposed either at the narrow portion or the wide portion thereof and means for shifting the element. 25

In testimony whereof I affix my signature.

PATRICK GRANGER.
